UNITED STATES PATENT OFFICE.

MARTHA H. CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX PART.

Application filed July 21, 1926. Serial No. 18,433. Term of patent 7 years.

To all whom it may concern:

Be it known that I, MARTHA H. CONNOR, a citizen of the United States, residing at Baltimore, in the State of Maryland, have invented a new, original, and ornamental Design for Box Parts, of which the following is a specification, reference being had to the accompanying drawing, forming a part thereof.

the border ornamentation being shown, the remainder involving a mere repeat of what is shown.

I claim:

The ornamental design for a box part as shown.

MARTHA H. CONNOR.
